UNITED STATES PATENT OFFICE

172,846

BASE FOR A PENHOLDER

Walter B. Spatz, Los Angeles, Calif., assignor to Frawley Corporation, Culver City, Calif., a corporation of California

Application September 3, 1953, Serial No. 26,687

Term of patent 14 years

(Cl. D74—1)

To all whom it may concern:

Be it known that I, Walter B. Spatz, a citizen of the United States, residing at Los Angeles, county of Los Angeles, and State of California, have invented a new, original, and ornamental Design for a Base for a Penholder, of which the following is a specification, reference being had to the accompanying drawing, forming a part thereof.

Fig. 1 is a top plan view, of a base for a penholder showing my new design,

Fig. 2 is a side elevational view thereof,

Fig. 3 is a front end elevational view thereof, and

Fig. 4 is a rear end elevational view thereof.

I claim:

The ornamental design for a base for a penholder, as shown.
